UNITED STATES PATENT OFFICE.

FRANK W. HOWARD, OF NEW YORK, N. Y.

UMBRELLA.

1,297,471.

Specification of Letters Patent. Patented Mar. 18, 1912.

Application filed May 4, 1915. Serial No. 25,689.

To all whom it may concern:

Be it known that I, FRANK W. HOWARD, a citizen of the United States, residing at New York city, in the county of New York and State of New York, have invented new and useful Improvements in Umbrellas, of which the following is a specification.

This invention relates to umbrellas. The general purpose of the invention is to produce an umbrella which can be very economically manufactured and placed upon the market at a very low figure, the idea being that such umbrellas could be kept constantly for sale for a very low price at many points such as news-stands, cigar stores, railroad depots and other frequented places so as to be readily available for persons who have been unexpectedly caught in the rain.

20 A principal object of the present invention is to provide a very simple and inexpensive method for making such an umbrella.

The umbrella cover is preferably formed of water-proof paper and one of the objects of the invention is to provide a method for producing a water-proof paper umbrella which, when creased and tightly rolled, ready for sale, will present substantially the same neat appearance as a tightly rolled silk or cotton umbrella.

One of the requirements of such an umbrella is that it shall be neat and compactly rolled near the crown. One of my objects is to prevent this creasing and tight rolling near the crown from tearing or otherwise injuring the paper.

Further objects of the invention will appear more fully hereinafter.

40 The invention consists in the procedure and details hereinafter described, all of which contribute to produce a simple and inexpensive method for producing an umbrella.

45 A preferred embodiment of the invention will be particularly described in the following specification while the broad scope of the invention will be pointed out in the appended claims.

50 In the drawings,

Figure 1 is a vertical section taken at the crown of the umbrella showing a portion of the stick and parts of the ribs in elevation, and a portion of the stick is broken away.

55 Fig. 2 is a vertical section, certain parts

being broken away, and illustrating the method as applied to the attaching of the ribs of the umbrella to the stick.

Fig. 3 is a plan of the parts shown in Fig. 2, certain parts being broken away.

Fig. 4 is a cross section of the stick at the crown and taken about on the line 4-4, Fig. 6.

Fig. 5 is a longitudinal section, partially in elevation showing the crown of the umbrella and particularly illustrating the method as applied to the attaching of the cover to the crown of the umbrella.

Fig. 6 is a view similar to Fig. 5 but illustrating the next step in attaching the cover to the crown and also indicating a feature of the method which may be employed if desired for very securely fastening the crown sleeve on the stick.

Fig. 7 is a vertical section illustrating a detail of my method which may be employed when using water-proof paper to construct the umbrella cover.

Fig. 8 is a side view of an umbrella constructed according to my method, the handle end of the stick being broken away.

Fig. 9 is a plan showing a preferred form of a cover-section, a number of which are formed and connected together to form the complete cover.

Fig. 10 is a bottom plan of the open umbrella, the stick being shown in cross section.

Fig. 11 is a side elevation of the completed umbrella.

Fig. 12 is a cross section taken at the point of connection of two adjacent cover sections.

Figs. 13 and 14 are details indicating the preferred method for securing the edges of the cover to the ribs.

Referring more particularly to the parts, in practising my method, I prefer to provide an improved method for attaching the ribs of the umbrella frame to the stick, the general object being to reduce the number of parts and to simplify the operations ordinarily incident to attaching umbrella ribs. For this purpose I prefer to provide a support or stand 20 which may comprise a thick horizontal plate 21 supported a short distance from the floor on suitable legs 22 (in Fig. 2 represented as broken away). The stand also preferably includes a plurality of posts 23 which may be provided with means such as hooks 24 for sup-

- porting a plurality of umbrella ribs 25. These umbrella ribs 25 are preferably formed of round steel or wire of small diameter, for instance, they may be of approximately one-sixteenth of an inch in diameter, with thin flat ends 26; and near their middle points these ribs are bent upon themselves so as to form eyes 27 which are useful in completing the umbrella for securing the stretchers 28 to the ribs (see Fig. 10). The umbrella may have as many of these ribs as desired. In the present instance, I have illustrated the umbrella as being formed of six ribs (see Fig. 3).
- 15 The center of the stand 20 which is to support the ribs in the manner indicated is preferably provided with a central opening 29 formed in a central block or rest 30. I produce a sleeve 31 which is to be the 20 crown sleeve of the umbrella. This sleeve is of simple cylindrical form except that at its upper end, as seen in Fig. 2, the material is swaged outwardly to form a mouth, lip or enlargement 32. The ribs 25 toward the flat 25 ends 26 are given a permanent bend as indicated at 33 in Fig. 2. By means of the hooks 24 the ribs are all supported so that the flat faces of these flat ends 26 lie against the inner face of the wall of the sleeve 31.
- 30 With the sleeve 31 and ribs 25 all supported in the relative position indicated, I force down through the sleeve 31 the crown-end of the umbrella stick 34 from a position above the sleeve as indicated by the dotted lines 34a in Fig. 2, and as further indicated by the arrow adjacent to the dotted outline. This stick 34 is preferably of wood or similar inexpensive and compressible material and is of sufficiently large diameter to fit tightly 35 in the opening 35 (see Fig. 3). Considerable force is therefore necessary to force the stick through the opening 35 in the manner suggested, and this has the effect of crushing the face of the stick by the flat ends 26 of 40 the ribs. In this way the ribs tend to form flat faces on the stick and may plow or impress shallow grooves or channels 36 for themselves which extend longitudinally from the tip of the stick inwardly (see Figs. 1 45 and 4).
- 50 When the stick has been applied in this way, the sleeve and ribs will remain in place. The crushing of the face of the stick at least flattens the face of the stick adjacent the ribs and this tends to prevent 55 the sleeve and ribs from rotating. Under ordinary circumstances, this method of fastening just described will be sufficient.
- If it is desired to make the crown of the 60 umbrella doubly secure, I prefer to accomplish this by forming small notches or recesses such as the recess 37 in the outer faces of the flat ends 26 of the ribs in such a way that when the ribs are arranged as in Fig. 2, the recesses will come against the inner face of the sleeve. Then after the stick is

fastened in the manner described above, the material of the sleeve is offset inwardly in a circumferential line opposite the notches by means of a chisel-pointed tool 38 indicated by the dotted line in Fig. 6. This tool 70 38, by offsetting the sleeve inwardly, causes an interlocking engagement between the sleeve and ribs which evidently will prevent the sleeve from moving longitudinally with relation to the ribs. 75

After the stick has been shoved "home" in the sleeve, the natural resiliency or elasticity of the stick beyond the point 39 (Fig. 6) at the upper end of the sleeve, tends to restore the end of the stick to its normal diameter 80 and shape, and this tendency is also augmented when the exposed portion of the umbrella becomes wet when the umbrella is used in the rain. This tendency of the stick to swell beyond the sleeve of course operates to 85 assist in securing the sleeve and ribs against longitudinal movement on the stick.

For the cover of the umbrella I prefer to use water-proof paper. Ordinarily, if an umbrella cover is constructed from water-proof paper and attached to an umbrella frame, it is found in practice that if it is attempted to roll up the umbrella, the creasing and twisting of the cover in the vicinity of the crown tends to tear the paper, particularly if it is attempted to crease and neatly roll the umbrella in a tight roll such as is commonly done with ordinary umbrellas. I believe I am the first to produce a paper-covered umbrella which is capable of being 90 rolled neatly and tightly like an ordinary cloth covered umbrella without injury to the paper. I am aware that parasols have been constructed of paper but such parasols when folded have been bulky and have produced 95 a roll of much larger diameter than that of an ordinary cloth covered umbrella. In such parasols, though the paper may be creased, it is not creased and rolled about the stick. 100

I prefer to give the water-proof paper a 110 treatment such as will render it capable of withstanding the strains due to creasing and tightly rolling the paper about the stick. This is preferably effected by moistening the paper. It is a paradoxical fact that although the paper is water-proof, it is affected by moisture to a certain extent, the effect of the moisture being to render the paper more pliable and to reduce its tendency to crack when creased or roughly handled. This 115 softening treatment if desired may be accomplished by piling the sheets or blanks 120 40 from which the cover is to be formed in a horizontal pack 41, with moistened sheets 42 of absorbent material such as cloth disposed 125 between the sheets of paper. If such a pack is permitted to stand for a considerable time, for example several hours, the paper sheets become very pliable and can be worked upon in very much the same manner as cloth. 130

In forming the cover, I prefer to cut from the blanks or sheets 40 a plurality of cover sections 43 preferably of substantially the shape indicated in Fig. 9, that is, of substantially triangular shape except that the long sides of the triangle are in the form of gradual ogee curves consisting of a long convex curve 44, extending from the base line 45 of the section, and a smaller concave curve 46 near the crown end of the cover section. Six of these cover sections are then attached together along their edges 44, preferably by sewing or stitches 47 applied through a deep overlaid edge 48 (see Fig. 12). In this way a cover 43^a is formed having a central crown-opening with an edge 49 (see Fig. 5). In addition to this, I prefer to place a plurality of eyelets 50 in the edges of the cover, and these eyelets correspond in number and position to the umbrella ribs.

In order to attach the umbrella cover to the crown sleeve, I prefer to turn the umbrella cover wrong side out and then apply the central opening of the cover to the crown sleeve in a reverse position such as that indicated in Fig. 5, that is, with the edge 49 of the umbrella cover lying adjacent to the enlarged end or lip 32 of the sleeve 31. I then attach this edge 49 preferably by tying the same with several turns of a cord 51 applied around the sleeve at this point, preferably in the manner indicated in Fig. 5. After tying the umbrella cover to the crown sleeve in this way, the cover is then turned right side out and then brought down into substantially the position indicated in Fig. 6. In tying the umbrella cover to the sleeve, it is preferable that the edge 49 should project slightly beyond the edge of the lip 32. This is done so as to prevent the stretched portion of the cover from coming into direct contact with the edge 32 which might tend to tear the paper. The edge of the umbrella cover is then brought down and applied to the ribs 25 near their outer ends, and so that the eyelets 50 in the cover lie with their flat sides against the sides of the ribs very near the extremities 50 of the ribs (see Fig. 13). I then bend outwardly the end 52 of each rib and force the extreme end of the rib into the eyelet 50 so that at the end of each rib an eye 53 is formed engaging the corresponding eyelet. If desired, guiding means such as loops 54 may be provided on the under side of the cover (see Fig. 10) which have sliding engagement with the ribs.

After the cover has been applied, I may provide a cap sleeve or outer sleeve 55 of larger diameter than the sleeve 31 and this cap sleeve has a reduced neck 56 which fits on the stick like a ferrule, and the lower portion of the cap sleeve may be expanded outwardly to form a bell mouth or apron

57 which extends over the tied point of the cover.

On the stick of the umbrella, there may be provided a runner 58 to which the stretchers 28 of the umbrella attach, the outer ends 70 of the said stretchers being attached to the aforesaid eyes 27 of the ribs.

If desired, the corners of the umbrella sections 43 may be provided with reinforcements 60 preferably in the form of triangular shaped gussets of cloth or paper. This feature and other mechanical features disclosed in this application are covered in my co-pending application Ser. No. 29,790, filed May 22, 1915, entitled "Umbrella." 80

The handle end of the stick 34 is preferably provided with a handle in the form of a knob 61.

In forming the umbrella with a paper cover according to my method, it is desirable 85 to form creases such as the creases 62 in Fig. 8, and disposed midway between the positions of the ribs. These creases should be formed while the paper is still pliable, that is, while it is still under the effect of the 90 softening treatment to which we subject it. If the umbrella is rolled up tightly and the paper is still under the influence of this treatment, the cover is capable of being rolled very tightly at a point such as the 95 point 63 near the umbrella crown, without injuring the paper, and the rolled up cover produces a very neat and tight tapering roll very similar in appearance to that of an ordinary umbrella. 100

While I prefer to soften the paper forming the cover also because this has the effect of making the paper soft like cloth and adapting the paper more readily to the operation of sewing, it is more important 105 however that the softening should occur near the crown of the umbrella. Evidently, if desired, the softening of the paper before forming the cover could be dispensed with and the cover after being attached to the 110 umbrella frame could be moistened or wet in the vicinity of the crown.

The completed umbrella may be opened like an ordinary umbrella because the flat parts of the ribs will flex readily to permit 115 the ribs to swing out or in.

The umbrella may be held normally rolled up by means of a suitable tying cord 43^b and button 43^c and after having been rolled the cover tends to resume this position. 120

While I do not limit myself to any certain kind of water-proof paper, I prefer to use an asphaltum paper or collodion paper. The collodion coated paper appears to be more sensitive and is more quickly influenced by the softening treatment. With collodion paper it is not necessary to moisten it to any great extent, but it may suffice simply to work the paper where the paper is exposed to a damp atmosphere. With this 125 130

paper it is preferable to complete the umbrella and then moisten the cover around the crown or the entire cover before creasing and rolling the umbrella.

5 The asphaltum paper is preferably moistened by placing the sheets in a pack as described above. If desired, the sheets of damp cloth may be omitted and a plurality of the sheets of paper simply sprayed with water or rubbed with a damp cloth or dipped in water, and then placed in a pack. The asphaltum paper absorbs moisture very slowly and it may take hours or days to get the paper to the proper condition. This 10 depends somewhat on atmospheric conditions. The best results are attained by keeping the paper stored and working it in a moist atmosphere. I prefer to use a paper known as molding paper because it stretches somewhat more than other papers.

15 Although these water-proof papers may take up moisture rapidly, the softening effect seems to remain in the paper for a considerable time.

20 25 It is understood that the embodiment of the invention set forth herein is only one of the many embodiments or forms the invention may take, and I do not wish to be limited in the practice of the invention nor 30 in my claims to the particular embodiment set forth.

What I claim is:

1. The method herein described of making an umbrella which consists in attaching 35 ribs to the stick together with a crown sleeve having an enlarged end disposed toward the handle end of the stick, making an umbrella cover with eyelets in its edges corresponding to the umbrella ribs and with a 40 central crown opening, tying the edge of the central opening to the sleeve adjacent the enlarged end thereof with the umbrella cover wrong side out, then turning the umbrella cover right side out, and bending the 45 ends of the ribs outwardly to form eyes engaging the eyelets at the edge of the cover.

2. The method herein described of making an umbrella frame which consists in supporting a tubular crown sleeve, supporting 50 a plurality of ribs having flat ends so that the flat ends of the ribs extend longitudinally within the sleeve with the flat sides of the ribs lying against the inner

face of the wall of the sleeve, and forcing a tightly fitting stick through said crown 55 sleeve to crush the face of the stick by said flattened portions and thereby secure said ribs to the stick.

3. The method herein described of making an umbrella frame which consists in 60 supporting a tubular crown sleeve, supporting a plurality of ribs having flat ends so that the flat ends of the ribs extend longitudinally within the sleeve with the flat sides of the ribs lying against the inner face 65 of the wall of the sleeve, and forcing a tightly fitting stick through said crown sleeve to crush the face of the stick by said flattened portions and thereby secure said ribs to the stick, and then offsetting the 70 sleeve to secure the same against longitudinal movement on the stick.

4. The method herein described of making an umbrella frame which consists in 75 supporting a tubular crown sleeve, supporting a plurality of ribs having flat ends with recesses in the sides so that the flat ends of the ribs extend longitudinally within the sleeve with the flat recessed sides of the ribs lying against the inner face of the wall of 80 the sleeve, and forcing a tightly fitting stick through said crown sleeve to crush the face of the stick by said flattened portions and thereby secure said ribs to the stick, and then offsetting the sleeve inwardly into 85 the recesses to secure the sleeve against longitudinal movement.

5. The method herein described of making an umbrella frame which consists in 90 supporting a tubular crown sleeve, supporting a plurality of ribs so that the ends of the ribs extend longitudinally within the sleeve and lie against the inner face of the wall of the sleeve, and forcing a tightly fitting stick through said crown sleeve to 95 crush the face of the stick with the ends of said ribs and thereby secure said ribs to the stick.

In testimony whereof I have hereunto set my hand in presence of two subscribing 100 witnesses.

FRANK W. HOWARD.
